COIN CONTROLLED PHONOGRAPH

Fred H. Osborne, Snyder, and John H. Riggs, Kenmore, N.Y., assignors to The Wurlitzer Company, Chicago, Ill., a corporation of Ohio

Filed June 27, 1960, Ser. No. 38,909

18 Claims. (Cl. 194—1)

The present invention relates to coin controlled automatic phonographs.

Conventional phonographs of this character are equipped with coin receiving means which responds to the deposit of coins to register playing credits that condition the machines for selecting records for playing. The customer then operates selector buttons or the like, to make individual record selections one at a time within the number of record selections allotted by the credit established in the machine. The machine then operates automatically to play the record selections made.

One object of the invention is to provide a new and improved coin controlled, automatic phonograph of the character recited which enables the customer to make desired record selections one at a time in the conventional manner, while at the same time providing for selection of an entire group of records at once by the customer, provided sufficient credit has been established in the machine to cover the playing price of the group of records, as such.

Another object is to provide an improved phonographic machine of the above character which enables the customer to dispense with the selection of recordings one at a time by selecting at once an entire preselected group of recordings which conform to his preferences.

Another object is to provide an improved coin controlled phonograph which enables the customer to select for playing a group of the most popular recordings, even though the customer may not know the titles of the recordings, while at the same time enabling the customer who so desires to choose recordings individually.

A further object is to provide an improved coin controlled phonograph of the character recited which gives the player who pays for and selects a sizable group of records at once, the benefit of a reduced playing price for the records selected.

Another object is to provide a phonograph of the above character in which a large number of records supported in a magazine can be selected for playing by new, improved, and extremely versatile record selecting means which operates with great efficiency to select records either individually or in groups, as desired.

Another object is to provide in a coin controlled phonograph, which enables the customer to select recordings individually for playing, new and improved recording selector structure which is conditioned by the establishment of a predetermined minimum credit in the phonograph to respond to the actuation of a single selector control automatically to select quickly a whole preselected group of records.

A further object is to provide in a coin controlled phonograph, having means for effecting the selection of desired recordings individually, improved selector means which responds to actuation of a single selector control to block operation of the individual recording selector controls and operates through the individual recording selector structure to select at once an entire preselected group of recordings.

2

Another object is to provide an automatic phonograph of the above character which utilizes new and improved recording selector means to effect selection of an entire preselected group of recordings at once through the operation of structure conventionally provided in the machine for selecting recordings individually. A related object is to provide an improved machine, as recited in the previous objects, which utilizes conventional credit cancelling structure which normally cancels credit for the selection of individual records to cancel the credit for the selection of a group of records at once.

An additional object is to provide an improved coin controlled automatic phonograph which achieves the foregoing objects by means of a relatively economical record selector structure having a simple, straightforward and reliable mode of operation.

Other objects and advantages will appear from the following description of the exemplary embodiment of the invention illustrated in the drawings, in which:

FIGURE 1 is a perspective view of an improved coin controlled phonograph forming the exemplary embodiment of the invention, certain basic components of the internal selector structure being illustrated in phantom;

FIG. 2 is a simplified, horizontal sectional view, taken with reference to the line 2—2 of FIG. 1;

FIG. 3 is a fragmentary sectional view, taken along the line 3—3 of FIG. 2;

FIG. 4 is a plan view of record group selector structure incorporated into the phonograph;

FIG. 5 is a side view of the selector structure of FIG. 4;

FIG. 6 is a fragmentary sectional view, taken along the line 6—6 of FIG. 4;

FIG. 7 is a side view of credit registering structure incorporated into the phonograph; and

FIG. 8 is a diagrammatic illustration of record group selector circuits.

Referring to the drawings in greater detail, the coin controlled phonograph 10 forming the exemplary embodiment of the invention is housed in an upright case 12. The construction and working mechanism of the improved phonograph 10 are in large measure the same as that used in conventional coin controlled phonographs currently in use.

The records 14 made available for playing in the phonograph 10 are supported in a toroidal magazine 16 mounted within the case 12, as indicated in phantom in FIG. 1, for rotation about a vertical axis.

Individual records selected for playing are temporarily transferred one at a time from the magazine 16 onto a turntable 18 where the records are played by a tone arm 20, FIG. 1. The playing of individual records, including the transfer of a record to the turntable and return of the record to the magazine, is accomplished automatically by conventional record transfer and playing mechanisms incorporated in the machine.

The phonographic machine 10 is conditioned for the selection of records by the customer for playing by the depositing of a coin in a coin receiving slot 22 in a control panel 24 on the front of the case 12. A coin deposited in the slot 22 is sensed by conventional coin sensing means 26 which operates through conventional crediting means to effect a rotary displacement of an accumulator or credit wheel 28, FIG. 7.

The mechanisms which effect a rotary displacement of the accumulator wheel 28 in a crediting direction as an

incident to the depositing of coins in the machine are well known to those skilled in the art and need not be described here in order to convey an understanding of the present invention. It is sufficient to note that the coin sensing means and crediting structure, identified generally by the number 26, operates to displace the accumulator wheel 28 rotatably in the counterclockwise direction, as indicated by the arrow 30, FIG. 7, as an incident to the depositing of a coin in the machine. Moreover, the degree to which the accumulator wheel is rotated in a crediting direction, and hence the value of the credit established, is automatically conformed to the denomination of the coin deposited, in accordance with a predetermined schedule of credit values for different coins.

When the accumulator wheel 28 is in its normal or "no credit" position, illustrated in FIG. 7, a laterally extending pin 32 on the wheel engages and opens a select switch 34. Immediately upon rotation of the accumulator wheel 28 away from its "no credit" position, as an incident to the establishment of playing credit in the machine, the pin 32 moves away from a cam actuator 36 on the switch 34 allowing the switch to close.

This conditions the machine for the selection by the customer of individual recordings for playing. The recordings are listed and identified individually by a code letter and a code number. A bank of letter buttons 38 and a bank of number buttons 40 are provided on the control panel 24 of the instrument. In this instance, the machine accommodates one hundred records which provide two hundred record selections. To permit selection of any one of the recordings, twenty letter buttons 38 and ten number buttons 40 are provided.

To make an individual record selection, the customer depresses a letter button 38 and a number button 40 corresponding to the letter and number code of each desired selection.

The depression of a letter button and a number button corresponding to the desired selection sets a selector pin 42 corresponding to the desired recording.

As illustrated in FIGS. 1 to 3, an annular series of selector pins 42 equal in number to the record selections available for playing, in this instance two hundred, are mounted in a record selection control assembly 44 housed within the case 12 below the record magazine 14.

The selector pins 42 are set selectively, in a conventional manner, by means of an annular series of twenty letter solenoids 46 mounted below a rotary solenoid carrier disk 48 concentric with the series. The letter solenoids 46 coact respectively with a corresponding series of twenty upright pin setting levers 50 extending up through the disk 48 into coaxing relation to the lower ends of twenty selector pins 42 alined therewith.

The buttons 38 are connected through conventional selector circuits to energize the respective solenoids 46. Energization of a particular solenoid 46 causes the coaxing lever 50 to operate against the lower end of an adjacent selector pin 42, disengaging the pin from a retaining disk 52 to allow a coaxing spring 54 to shift the pin upwardly to a "set" position.

The entire series of pin setting levers 50 is moved by rotation of the disk 48 into any one of ten selector positions differentially spaced from each other. For each rotary position of the disk 48, the pin setting levers 50 are alined with a set of twenty selector pins 42, the levers being alined with a different set of pins for each rotary position of the disk 48. Each lever 50 is shaped and mounted in a conventional manner in relation to the corresponding letter solenoid 46 so that the solenoid is effective for operating the lever when the latter is in any one of its ten differentially spaced positions.

The carrier disk 48 is rotated to any one of its ten operating positions by an electric motor 56, FIG. 2, connected through gearing 58 with the disk, as shown.

Rotation of the carrier disk 48 selectively in a desired operating position is accomplished by the coaction of ten

number solenoids 60, disposed in overlying relation to the disk 48, with a plurality of differential stops 62 on the upper side of the disk. The number solenoids 60 are energized by the respective number buttons 40 through operation of conventional control circuits requiring no description here.

Hence, upon depression of a letter button 38 and a number button 40, one of the solenoids 60 is energized and the motor 56 operates to locate the series of pin setting levers in positions corresponding to the actuated number button. The letter solenoid 46 corresponding to the actuated letter button then operates to set the selector pin 42 corresponding to the desired record selection. This structure in its operation conforms to that used in conventional coin controlled phonographs for making record selections one at a time.

Any number of the selector pins 42 can be set. Conventional record playing mechanisms in the machine operate automatically to play the record selections corresponding to the set pins 42 and to return the individual pins to their normal positions so long as any pin remains set.

Conventional credit cancelling circuits incorporated into the machine 10 and identified in FIG. 8 by the number 66 operate in response to the making of a record selection to cancel playing credit for the record selection made. This is accomplished through energization of a credit cancelling solenoid 68, FIG. 7, which actuates a pawl mechanism 70 to displace the accumulator wheel 28 in a credit cancelling direction. In this connection, it should be pointed out that the accumulator wheel 28 is biased in the crediting direction by conventional structure (not shown) located on the far side of the plate 72 in FIG. 7, and overbalancing the action of the spring 74, which biases the wheel 28 in the clockwise or credit cancelling direction. When all the playing credit has been cancelled, the pin 32 again opens the select switch 34 to disable the record selecting circuits.

In accordance with the invention, provision is made in the improved coin controlled photograph 10 for enabling the customer who so desires to select, as a group, a preselected group or sub-group of records in the magazine 16. Moreover, this is achieved by means of new and improved selector structure which also provides for the selection of individual recordings and makes efficient use of selector structure of a conventional character to effect a selection of recordings, either individually or in a group or groups.

Thus, for example, the improved machine can be set up to permit the customer who so desires to select at once the "top ten" or the ten most currently popular recordings. This group of records can be selected as such, even though the customer does not know the titles of the individual recordings, and eliminates for the customer who wants to hear the most popular recordings the necessity for determining the identity of these recordings and selecting them one at a time.

The structure used to select an entire group of records at once is normally disabled, and is conditioned to select a group of recordings only when sufficient credit has been established in the machine to cover the playing price of the group. However, as will presently appear, the group of records can be priced for playing independently of the cumulative playing price of the individual records in the group.

In the present instance, the machine is set up to permit selection of a group of records only when at least 50¢ credit has been established in the machine. This permits the customer establishing credit in this amount to select a group of ten records. If the records are selected individually, the machine allows only seven selections to be made for 50¢. However, it will be understood from the ensuing description that the number of records which can be selected as a group and the playing price of the group of records can be varied as desired.

As previously stated, the depositing of coins in the machine effects a displacement of the accumulator wheel 28 in a counterclockwise crediting direction with reference to FIG. 7. The depositing of a 50¢ coin moves the accumulator wheel 28 to an angle sufficient to cause the pin 32 to engage and close a group selector activating switch 80.

Closure of the switch 80 does not operate the group selector structure, to be described, but only activates or conditions it in readiness for making a group selection by the customer. At this point, the banks of letter buttons 38 and number buttons 40 remain fully effective for making individual recording selections in the conventional manner. In the event the customer operates a letter button and a number button to select an individual recording, the cancelling solenoid 68 displaces the wheel 28 in the clockwise direction to open the switch 80 and disable the group selector structure.

However, with 50¢ credit in the wheel 28, the switch 80 is closed to light a group selector light 82 on the control panel 24, FIG. 1, to indicate to the customer that he can select the top ten recordings.

To select the top ten records, the customer has merely to depress a "top ten" button 84 on the control panel. This puts the group selector structure into operation to quickly go through an operating cycle to set the ten selector pins 42 corresponding to the top ten recordings in the magazine 16.

Referring to the simplified diagrammatic illustration of the circuits involved, shown in FIG. 8, it will be noted that closure of the previously mentioned group selector activating switch 80 grounds a conductor 90 connected to one side of the group selector light 82. The other side of the light 82 connects with a power conductor 92 and is energized upon closure of the switch 80, as previously recited.

Depression of the group selector button 84 closes a switch 94, in series with the switch 80, to complete an energizing circuit through a group selector cycling motor 96 and the operating solenoid 98 of a relay switch 109. The motor 96 and the solenoid 98 are connected in parallel with each other.

As shown in FIGS. 4 and 5, the motor 96 is mounted on a base 102 and connected through a speed reducing transmission 104 with a shaft 106, which, as will presently appear, is rotated through a complete cycle in response to depression of the group selector button 84.

The shaft 106 has a starting or home position, illustrated in FIGS. 4 and 5, in which a switch actuating projection 108 on a radial arm 110 engages a ledge 112 on a resilient cantilever 114 to hold the cantilever against a full cycle switch 116 to maintain this switch in an open position. As soon as the shaft 106 starts to rotate, upon depression of the button 84, the projection 108 moves off the cantilever ledge 112 allowing the full cycle switch 116 to close. As shown in FIG. 8, this switch connects the output side of the switch 94 to ground to continue energization of both the motor 96 and the relay solenoid 98 independently of the switches 94 and 80.

As the shaft 106 completes a single revolution of motion it engages an inclined cam 118 on the cantilever 114, to again open the full cycle switch 116 and deenergize the motor 96 and relay solenoid 98. By this time, credit will have been cancelled from the accumulator wheel 28 allowing the switch 80 to open so that the cycling motor 96 cannot be energized until playing credit has been reestablished in the wheel 28.

Rotation of the shaft 106 through a complete revolution operates two pulsing switches 120, 122 through complete operating cycles. As will be described presently in greater detail, the pulsing switch 120 is interconnected with the credit cancelling solenoid 68 to cancel credit from the wheel 28 in accordance with the playing price of the record group. The other pulsing switch

122 operates to energize the letter solenoids 46 corresponding to the record selections in the group.

The relay switch 100, which is energized concurrently with the motor 96, operates to transfer a number of functions from the circuitry normally used to select recordings one at a time to the circuitry which selects a group of records at once.

Thus, as illustrated in FIG. 8, individual record selector circuits, controlled by the letter and number buttons 38, 40 and identified in this figure by the number 124, are controlled by energization of a conventional latch solenoid circuit 126 which must be energized in order to make the buttons 38 and 40 operative for selecting individual recordings.

As shown, the latch solenoid circuit 126 is energized through a normally closed switch 128 ganged with the previously mentioned switch 94 and a normally closed relay switch 100-2. Hence, depression of the group selector button 84 opens the switch 128 to immediately block energization of the latch solenoid circuit 126, and thus block operation of the buttons 38 and 40 to make a record selection. The immediate energization of the relay solenoid 98 opens the relay switch 100-2 to assure continued deenergization of the latch solenoid circuit 126 until the motor 96 has completed its normal operating cycle.

The previously mentioned credit cancelling circuit 66, FIG. 8, which is used to cancel credit for the selection of individual recordings in the usual manner, is connected to the credit cancelling solenoid 68 through a normally closed relay switch 100-4. This relay switch is opened, upon energization of the solenoid 98, to block operation of the credit cancelling circuit 66. At the same time, a relay switch 100-6 is closed to connect the credit cancelling solenoid 68 to the output of the pulsing switch 120, to enable the latter to cancel credit for the group selections.

Energization of the relay solenoid 98 also closes a relay switch 100-8 to effect operation of a letter solenoid positioning circuit 130 which effects movement of the lever carrier disk 48 to a predetermined record group selector position. For this purpose, the circuit 130 is connected to one of the number solenoids 60 which corresponds to the rotary position in which the carrier disk 48 is located for selection of the record group.

The two pulsing switches 120, 122 are, in fact, closely interrelated to each other structurally, as illustrated in FIGS. 4 and 6, but operate functionally independently of each other. The function of these switches can be visualized more readily with reference to FIG. 8. Thus, as shown, the pulsing switch 122 comprises a switch contact 132 which is moved by the shaft 106 through a rotary path which moves the contact 132 into engagement successively with an annular series of independent stationary contacts 134. In this instance, ten of the contacts 134 are independently connected to the ten letter solenoids 46 corresponding to the respective record selections in the record group which is to be selected at once. The sliding contact 132 is continuously grounded through a contact 136 engaging a grounded contact patch 138.

At this point, it will be understood that the relay switch 100-8 effects movement of the carrier disk 48 to bring the series of levers 50 into rotary alignment with twenty selector pins 42 including the ten pins corresponding to the record selections of the group. The pulsing switch 122 then operates to energize ten of the letter solenoids 46 to set the ten selector pins which effect playing the desired record group.

The credit cancelling pulsing switch 120 comprises a wiper contact 140 which is moved by the shaft 106 through a rotary path which carries the contact 140 into engagement successively with a plurality of patch contacts 142 interconnected with a common conductor 144, which is connected through the output terminal of this switch with the previously mentioned relay switch

100-6. The wiper contact 140 is grounded through the same contact 136 which grounds the other pulsing switch 122, FIGS. 6 and 8. Preferably, all the stationary contacts 134, 138 and 142 are mounted on one face of an insulator board 145 where they are opposed by the movable contacts 132, 136 and 140 which are carried by the corners of a triangular, resilient support plate 147 secured to the shaft 106.

In the present instance, the pulsing switch 120 includes ten stationary contacts 142 and produces during each operating cycle ten output pulses which operate the credit cancelling solenoid 68 to cancel ten increments of credit from the accumulator wheel 28. However, it will be understood that any number of contacts 142 can be used in the pulsing switch 120 to cancel any number of credit units as the playing price of the group of records selected at once.

Thus, in response to a single depression of the group selector button 84, the group selector structure operates to set ten selector pins 42 corresponding to the top ten recordings in the machine and cancel ten units of credit from the credit wheel 28. The phonograph proceeds, as described, to play the record selections corresponding to the set pins.

It will be appreciated that the record selector structure is extremely versatile. It provides for the selection of records either independently or in groups, while at the same time allowing complete flexibility in the pricing of the records individually and in groups. The number of records in the group can be varied by varying the number of pulsing switch contacts 134 connected to the letter solenoids.

While the illustrated construction provides for selection of only one group or sub-group of records, as such, it will be appreciated that by duplicating the selector pulsing switch 122 and adding additional group selector buttons and switches 84 and 94, those skilled in the art can readily adapt the invention to enable the customer to select any number of groups or sub-groups of records by pushing a selector button corresponding to the particular group of records desired.

While the pulsing switch 122 energizes the coacting letter solenoids 46 in succession, this pulsing switch can be replaced if desired by a multiple pole switch which will energize all of the coacting letter solenoids 46 simultaneously.

It will be appreciated that the invention is not necessarily limited to use of the particular construction illustrated, but includes variants and alternatives within the scope of the invention as defined by the claims.

The invention is claimed as follows:

1. In a coin controlled automatic phonograph, the combination of a record magazine, an annular series of selector pins for controlling the selection of records from said magazine for playing, means for playing selected records, a movable carrier, a series of selector pin setting elements positioned by said carrier, means including a first series of solenoids for locating said carrier in a plurality of selecting positions, a second series of solenoids for operating said respective pin setting elements, a manually controlled selector circuit interconnected with said first and second series of solenoids for setting selected ones of said selector pins, normally deactivated record group selecting means, coin-controlled credit establishing means interconnected with said group selecting means to activate the latter in response to establishment of a predetermined credit value in said credit establishing means, said record group selecting means including first pulsing switch means connected to a plurality of said second series of solenoids to operate the latter, electric cycling means connected to said pulsing switch means to run the latter through individual operating cycles thereof, a group selector switch for energizing said cycling means after activation of said group selecting means, switch means controlled by said group selector switch to disable said

manually controlled selector circuit, switch means controlled by said group selector switch for energizing one solenoid of said first series to locate said series of pin setting elements in predetermined positions relative to said selector pins, and second pulsing switch means operated by said cycling means and interconnected with said credit establishing means to cancel credit from said credit establishing means as an incident to cycling of said cycling means.

10 2. A coin controlled automatic record playing machine comprising, in combination, a series of settable selector elements for controlling the selection of recordings for playing, means for playing recordings selectively in accordance with the setting of said selector elements, a movable series of electrically operated selector element setting elements for setting selector elements in alignment therewith, differential positioning means for moving said setting elements into alignment with different selector elements, manually controlled recording selecting means interconnected with said differential positioning means and connected to operate said setting elements for setting selected ones of said selector elements, normally disabled recording group selecting means, coin-controlled credit establishing means interconnected with said group selecting means to render the latter operative in response to the establishment of a predetermined credit value in said credit establishing means, said recording group selecting means including means interconnected with said differential positioning means to position said setting elements in alignment with selector elements corresponding to a preselected group of recording selections, said record group selecting means including first switch means connected to operate a plurality of said setting elements, a group selector switch for operating said record group selecting means when the latter is rendered operative by said credit establishing means, and second switch means operated by said recording group selecting means and interconnected with said credit establishing means to cancel credit therefrom as an incident to operation of said recording group selecting means.

3. In a coin controlled automatic recording playing machine, the combination of annular series of settable selector pins for controlling the selection of recordings for playing, means for playing recordings selectively in accordance with the setting of said selector pins, a movable carrier, a plurality of solenoid operated selector pin setting elements positioned by the carrier in operative alignment with different groups of said selector pins in accordance with the position of said carrier, solenoid means for positioning said carrier differentially, a manually controlled selector circuit for operating said solenoid means and said selector pin setting elements for setting selected ones of said selector pins individually, recording group selecting means, coin-controlled credit establishing means for conditioning said group selecting means for operation, said recording group selecting means including means for controlling said solenoid means to position said carrier differentially and including means for operating said selector pin setting elements, a group selector switch for operating said group selecting means to set a group of selector pins corresponding to a preselected group of recordings in said magazine, and switch means operated by said group selecting means and interconnected with said credit establishing means to cancel credit therefrom upon operation of said recording group selecting means.

4. In a coin controlled automatic recording playing machine, the combination of an annular series of settable selector pins for controlling the selection of recordings for playing, means for playing recordings selectively in accordance with the setting of said selector pins, a movable carrier, electrical means for positioning said carrier differentially, a plurality of solenoid operated selector pin setting elements positioned by said carrier in operative alignment with different groups of said selector pins in accordance with the position of said carrier, recording

group selecting means, coin-controlled credit establishing means for conditioning said group selecting means for operation, said recording group selecting means including means for controlling said electrical means to position said carrier differentially and including means for operating said selector pin setting elements to set a group of selector pins corresponding to a preselected group of recordings in said holding means, and manual control means for said group selecting means.

5. In a coin controlled automatic recording playing machine, the combination of recording holding means a plurality of settable recording selector elements, means for playing recordings selectively in accordance with the setting of said selector elements, a plurality of solenoid operated selector element setting devices, means for positioning said setting devices differentially with respect to said selector elements, record group selecting means, coin controlled means for conditioning said group selecting means for operation, said record group selecting means including means for operating said setting devices to set a group of selector elements corresponding to a preselected group of records in said holding means, and control means responsive to a single manual control action to operate said group selecting means.

6. In a coin controlled automatic recording playing machine, the combination of settable selector means for registering recording selections, means for playing recordings from said magazine in accordance with the recording selections registered by said selector means, normally inoperative group selecting means coacting with said settable selector means to register a whole preselected group of record selections in the latter in one operation, coin controlled crediting means coacting with said group selecting means to condition the latter for operation upon establishment of a predetermined minimum credit value in the crediting means, manual control means coacting with said group selecting means to control operation of the latter after the group selecting means has been conditioned for operation by said crediting means, credit cancelling means interconnected between said group selecting means and said crediting means to cancel credit from the latter as an incident to operation of said group selecting means, and manually controlled means responsive to a single manual control action for operating said settable selector means to register individual record selections one at a time.

7. In a coin controlled automatic phonograph, the combination of a record magazine, selector means for registering individual record selections, means for playing records from said magazine in accordance with record selections registered by said selector means, normally inoperative group selecting means coacting with said selector means to register a whole preselected group of record selections in the latter in one operation, said group selecting means including control means responsive to a single manual control action to institute such registration of said preselected group of record selections, normally inoperative individual record selecting means coacting with said selector means to register individual record selections in the latter one at a time, and coin controlled means coacting with said group selecting means and said individual record selecting means to condition the respective selecting means for operation.

8. In a coin controlled automatic recording playing machine, the combination of a means including a plurality of settable selector elements for registering individual recording selections desired by the customer, means for playing recordings corresponding to the set selector elements, manually controlled individual recording selecting means coacting with said settable selector elements to select and set selective individual selector elements, group selecting means for setting a preselected plurality of said settable selector elements in one operating cycle, coin receiving means interconnected with said group selecting means to condition the latter for operation only when

sufficient credit has been established in the coin receiving means to cover the playing price of the group of recording selections corresponding to said preselected plurality of selector elements, and manual control means coacting with said group selector means and responsive to a single manual control action to effect operation of said group selector means when the group selector means is conditioned for operation by said coin receiving means.

9. In a coin controlled automatic record playing machine, the combination comprising a series of settable selector elements for controlling the selection of recordings for playing, means for playing recordings selectively in accordance with the setting of said selector elements, a plurality of selector element setting devices, differential positioning means for moving said setting devices into operative alignment with different selector elements, manually controlled record selecting means interconnected with said differential positioning means and with said setting devices for selectively setting said selector elements individually, normally inoperative recording group selecting means, coin controlled credit establishing means interconnected with said group selecting means to render the latter operative, and said recording group selecting means including means interconnected with said differential positioning means to position said setting devices in alignment with selector elements corresponding to a preselected group of recording selections, and said recording group selecting means including means connected to a plurality of said setting devices to operate the latter, said group selecting means further including control means responsive to a single manual control action to effect operation of the remainder of said group selecting means.

10. In a coin controlled automatic recording playing machine, the combination of means for holding a plurality of recordings, an annular series of selector pins for controlling the selection of recordings for playing, means for playing selected recordings, a movable carrier, a plurality of solenoid operated pin setting devices positioned by said carrier in operative alignment with pins of said series corresponding to the position of said carrier, means including a series of solenoids for locating said carrier in a plurality of selecting positions, manually controlled selecting means for operating said solenoids and said setting devices for setting said selector pins individually, normally inoperative recording group selecting means, coin controlled credit establishing means interconnected with said group selecting means to render the latter operative in response to establishment of a predetermined credit value in said credit establishing means, said recording group selecting means including first pulsing switch means connected to a plurality of said pin setting devices to operate the latter, electric cycling means connected to said pulsing switch means to run the latter through individual operating cycles thereof, a single group selecting switch singly operable for energizing said cycling means, switch means controlled by said group selecting switch to disable said manually controlled selecting means, and second pulsing switch means operated by said cycling means and interconnected with said credit establishing means to cancel credit therefrom as an incident to operation of said group selecting means.

11. In a coin controlled automatic recording playing machine, the combination of selector means for registering recording selections, means for playing recordings in accordance with the recording selections registered in said selector means, a plurality of setting devices for registering recording selections in said selector means, differential positioning means for positioning said selector devices differentially with respect to said selector means, individual recording selecting means for operating said setting devices for registering individual recording selections in said selector means, recording group selecting means for operating said setting devices for registering a group of recording selections in said selector means, coin controlled credit establishing means for controlling operation of said

individual recording selecting means and for controlling operation of said recording group selecting means, said recording group selecting means including a cycling motor, a single recording group selecting switch singly operable energizing said motor, a full cycle switch for continuing energization of said motor through a complete operating cycle, a first pulsing switch operated by said motor and connected to operate said setting devices, and a second pulsing switch operated cyclically by said motor and connected with said credit establishing means for cancelling credit therefrom as an incident to cycling of said motor.

12. In a coin controlled automatic recording playing machine, the combination of selector means for registering recording selections, means for playing recordings in accordance with the recording selections registered in said selector means, a plurality of setting devices for registering recording selections in said selector means, differential positioning means for positioning said setting devices differentially with respect to said selector means, manually controlled means for registering individual recording selections in said selector means, recording group selecting means for registering a group of recording selections in said selector means and including control means operable in response to a single manual control action, said recording group selecting means including a cycling motor, a recording group selecting switch for energizing said motor, and a pulsing switch operated by said motor and connected to operate said selector setting devices.

13. A coin controlled automatic recording playing machine, comprising, in combination, an annular series of selector pins for controlling the selection of recording for playing, means for playing selected recordings, a movable carrier, a plurality of selector pin setting devices positioned by said carrier for setting said selector pins selectively, a series of solenoids for operating said setting devices, solenoid means for positioning said carrier and said setting devices differentially with respect to said pins, a cycling motor, coin controlled credit means establishing means for controlling energization of said motor, a recording group selecting switch for energizing said motor, a plurality of contacts connected to a plurality of said solenoids, contact means operated by said motor to move into engagement with said plurality of contacts successively to effect setting of a plurality of said selector pins, a second plurality of contacts connected with said credit establishing means to cancel credit therefrom, contact means operated by said motor for movement into engagement with said second series of contacts successively to effect cancellation of credit from said credit establishing means, and means interconnecting said recording group selecting switch with said solenoid means to effect differential positioning of said carrier for setting of a preselected plurality of said selector pins.

14. A coin controlled automatic recording playing machine comprising, in combination, a plurality of settable selector elements for controlling the selection of recordings for playing, means for selecting and playing recordings in accordance with the setting of said selector elements, a plurality of selector element setting devices including a plurality of operating solenoids therefor, means for positioning said setting devices differentially with respect to said selector elements, a cycling motor, coin controlled means for controlling energization of said motor, a recording group selecting switch for energizing said motor, a plurality of contacts connected to a plurality of said setting device solenoids, contact means operated by said motor to move into engagement with said plurality of contacts to effect setting of a plurality of said selector elements, and means coordinating said recording group selecting switch with said differential positioning means to position said setting devices for setting of a preselected plurality of said selector elements.

15. In a coin controlled automatic recording playing machine, the combination of selector means for registering individual recording selections, means for playing re-

cordings automatically in accordance with recording selections registered by said selector means, manually controlled individual recording selecting means coacting with said selector means to register individual recording selections in the latter one at a time, group recording selecting means coacting with said selector means to register a plurality of recording selections in said selector means as an incident to a single operation of said group selecting means and including control means operable in response to a single manual control action, and coin controlled means for controlling operation of said individual recording selecting means and for controlling operation of said group recording selecting means.

16. In a coin controlled automatic recording playing machine, the combination of selector means for registering individual recording selections, means for playing recordings in accordance with recording selections registered in said recording selector means, normally inoperative group selecting means coacting with said selector means to register a preselected group of recording selections in the latter in one operation and control means operable in response to a single manual control action, individual recording selecting means for registering individual recording selections in said selector means one at a time, coin controlled crediting means for establishing playing credit in accordance with the depositing of coins in the crediting means, said crediting means including means coacting with said group selecting means to condition the latter for operation as an incident to the establishment in said crediting means of a first credit value equal to the playing price of a recording group, and said crediting means including means coacting with said individual recording selecting means to condition the latter for operation as an incident to the establishment of a second predetermined credit value in the crediting means.

17. A coin controlled automatic recording playing machine comprising selector means for registering for playing individual recording selections, means for playing recordings in accordance with recording selections registered in said selector means, normally inoperative group selecting means coacting with said selector means to register in the latter for playing a predetermined plurality of individual recording selections, said group selecting means including control means responsive to a single manual control action to institute such registration of said plurality of recording selections, normally inoperative individual recording selecting means coacting with said selector means to register individual recording selections in the latter, and coin controlled means coacting with said group selecting means and said individual recording selecting means to condition the respective selecting means for operation.

18. A coin controlled machine for automatically playing recordings recorded on different sound recording paths, said machine comprising, in combination, selection registering means for registering individual sound path selections, said selection registering means including sound path group selecting means for registering in the registering means for playing as a single choice a predetermined group of sound paths, said selection registering means including manual control means operable independently of said group selecting means to register in the registering means for playing individual sound path selections selected independently of each other by operation of said manual control means, said group selecting means being operable to register a group of sound path selections in said registering means independently of operation of said manual control means, recording playing means controlled by said selection registering means to operate in response to the registration of one or more sound path selections in said registering means to play sound path selections registered in the registering means by said group selecting means or by said manual control means, coin control means coacting with said group selecting means and with said manual control means to make both said

group selecting means and said manual control means normally inoperative to register sound path selections in said registering means, said coin control means including means coacting with said manual control means to render the latter operative to register individual sound path selections in said registering means while at the same time rendering said group selecting means inoperative to register sound path selections in said registering means, and said coin control means including means for rendering

5
said group selecting means operative to register sound path selections in said registering means.
